UNITED STATES PATENT OFFICE.

HARRY M. TEMPLE AND PHILIP KEARNEY, OF DETROIT, MICHIGAN, ASSIGNEES TO
DETROIT CLOSED BUSHING COMPANY, OF DETROIT, MICHIGAN.

END CLOSURE FOR WIRE-CONDUITS.

1,341,398.

Specification of Letters Patent. Patented May 25, 1920.

Application filed August 18, 1916. Serial No. 115,663.

To all whom it may concern:

Be it known that we, HARRY M. TEMPLE and PHILIP KEARNEY, citizens of the United States, residing at Detroit, in the county 5 of Wayne and State of Michigan, have invented certain new and useful Improvements in End Closures for Wire-Conduits, of which the following is a specification.

This invention relates to improvements in 10 end closures for wire conduits for electric wires and the like. The primary object of the invention is to provide simple, efficient and inexpensive means for removably closing the ends of the wire conduits, and, more 15 specifically stated, to provide an improved removable plug or cap especially adapted to snugly fit into a bushing screwed onto the conduit end, the bushing being preferably formed with an internal shoulder coöperating 20 with the plug.

Other objects and advantages will appear from the following specification, wherein we have illustrated and described preferred embodiments of the invention. Reference is 25 to be had to the accompanying drawings illustrating preferred embodiments of the invention and wherein similar reference numerals designate similar parts throughout the several views.

30 In the drawings:—

Figure 1 is a longitudinal sectional view through an outlet-box and the associated end of an electric wire conduit provided with one form of the improved end closure; 35 Fig. 2 is a sectional view through the plug or cap employed; Fig. 3 is a similar view through the bushing employed; Fig. 4 is a similar view of another form of plug or cap that may be employed; Fig. 5 is a similar 40 view through a third form of plug or cap that may be employed; and Fig. 6 is a sectional view through the bushing and cap shown in Fig. 5 in position thereon.

In the drawings, the numeral 5 designates an outlet-box of a well-known variety, and 6 the associated end portion of a conduit for electric wires, the conduit being secured in the side wall of the outlet-box in the usual or any desired manner, as, for 45 example, by lock nuts 7 threaded on the conduit and abutting against opposite sides of the wall of the outlet-box. A bushing 8 is adapted to be threaded or otherwise removably secured on the conduit adjacent its end, 50 said bushing being preferably provided

with burs or ribs 9 for coöperation with a wrench or other instrument for attaching and removing the bushing. An internal shoulder 10 is preferably formed at or adjacent the extremity of the bushing at the 55 opposite end from the screw threads, which shoulder is adapted to coöperate with the plug or cap 11 which extends across the end of the bushing and effects a complete closure of the end of the bushing and the conduit. 60 The cap 11, in the example illustrated, bears with its rim upon the rounded shoulder 10 directly upon and throughout the entire circumference of the extreme end of the rounded shoulder 10. The plug or cap 11 is preferably formed in one piece having an end wall of sufficient diameter to extend across the open end of the bushing, and an annular flange 12 of lesser diameter adapted to fit snugly into the bushing so as to be held 65 therein by friction. Thus, in Fig. 1 the flange 12 is of slightly greater diameter than the inner diameter of the shoulder 10 of the bushing and the flange 12 is of slightly 70 resilient material so that when the plug or cap is forced into the bushing the flange 12 will be slightly compressed in passing the innermost wall of the shoulder 10. If desired, the shoulder 10 may be formed with a curved inner wall, and the flange 12 be 75 more firmly held therein by expanding the same to follow the contour of the curved wall—a suitable expanding tool being utilized to effect this expansion. The shoulder 10 is formed with a curved or rounded inner 80 wall to facilitate the passage of insulated wires through the bushing, abrasion of the insulation thus being avoided. Or a cap or plug substantially of the shape shown in Fig. 4 may be utilized, the wall 13 thereof 85 being forced inwardly beyond the curved shoulder 10 of the bushing, the shoulder thereupon fitting into the annular groove 13^a in the side wall of the cap. A beading 13^b or similar extension may be provided to 90 abut against the extremity of the bushing.

In Fig. 5 is shown another form of cap or plug provided with a wall 14 and a flange 15, the inner extremity of which is bulged outwardly and slotted at intervals around 95 the flange, whereby the resiliency of the flange 15 is increased to enable said flange to give inwardly in passing the shoulder 10 of the bushing and then expanding to 100 snugly engage the inner periphery of the 110

bushing and the curved inner surface of the shoulder.

- It will be noted that any of the forms of caps or plugs herein shown may be quickly and readily inserted into the bushing 8 and as readily removed therefrom by inserting a flat-edged tool between the outer wall of the cap and the end of the bushing. Also, despite the simplicity of the arrangement, 5 the cap or plug will be firmly held within the bushing as long as desired, through the frictional engagement of the flange of the cap with the internal shoulder on the bushing.
- 10 While it will be apparent that the preferred embodiment of our invention herein disclosed is well calculated to adequately fulfil the objects and advantages primarily stated, it is to be understood that the invention 15 is susceptible to modification, variation and change without departing from the spirit and scope of the invention as set forth in the subjoined claims.

Having described the invention, we claim:

- 25 1. As an article of manufacture, a conduit closure consisting of a bushing having an internal shoulder adjacent an end thereof, and a closure cap for said bushing comprising an end wall, and a flange extending into 30 said bushing conforming to the shoulder.
- 35 2. As an article of manufacture, a conduit closure consisting of a bushing having an internal shoulder, ribs on the exterior of said bushing extending from adjacent one end thereof toward the other end but falling short of said other end, and a closure cap for 40 said bushing having a rim engaging said other end of said bushing throughout its circumferential extent, and having a flange extending into said bushing conforming to said shoulder.

3. The combination with an outlet box, of a conduit communicating therewith, a conduit bushing on said conduit, a rounded end on said bushing, a rounded internal shoulder adjacent the end of said bushing, and a closure cap having a rim abutting against said rounded end throughout its circumference, and a flange on said closure cap having a groove following the contour of said 50 rounded shoulder.

4. As an article of manufacture, a conduit closure comprising a bushing adapted to be secured upon the end of a conduit, an internal shoulder adjacent an end of said bushing, and a closure cap for said bushing comprising a resilient flange forced into said bushing and conforming to said shoulder.

5. As an article of manufacture, a conduit closure consisting of a bushing having an internal shoulder adjacent an end thereof, and a closure cap for said bushing comprising a flange extending into said bushing, and a wall at the end of said flange within said bushing, said flange conforming adjacent 60 said end wall to said shoulder.

6. As an article of manufacture, a conduit closure comprising a bushing, ribs on the exterior of said bushing extending from adjacent one end thereof toward the other 70 end but falling short of said other end, an internal shoulder adjacent the other end of said bushing, and a closure cap for said bushing comprising a resilient flange forced into said bushing and conforming to said 75 shoulder, and a wall closing the end of said flange within said bushing.

HARRY M. TEMPLE.

PHILIP KEARNEY.
